UNITED STATES PATENT OFFICE.

WILLIAM L. PHILLIPS, OF CHICAGO, ILLINOIS.

COMBUSTION-ENGINE.

1,195,603.

Specification of Letters Patent. Patented Aug. 22, 1916.

Application filed May 15, 1912. Serial No. 697,388.

To all whom it may concern:

Be it known that I, WILLIAM L. PHILLIPS, a citizen of the United States, residing at Chicago, in the county of Cook and State 5 of Illinois, have invented certain new and useful Improvements in Combustion-Engines, of which the following is a specification.

This invention relates to combustion engines, and is more particularly designated as an automatically governed engine of this class, which is adapted to be operated at different fixed speeds, and for which various speeds the explosive mixture is automatically controlled to correspond therewith.

The principal object of the invention is to provide a machine of this class which is simple, reliable, easily operated and constructed, and efficient and effective in operation.

A further object is to provide means to compensate for speed variations from a predetermined rate of speed by automatically varying the supply of fuel to the engine.

A still further object is to provide a mixing device or carbureter which is adapted to be used in the present connection, embodying some novel features which adapt the engine to be operated at different speeds with economy of fuel consumption, thereby increasing the efficiency of the engine.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings Figure 1 represents an engine of the class described, to which a governing device and a mixing device are applied embodying the features of my invention; Fig. 2 is an end view of a centrifugal governing device; Fig. 3 is a sectional view of the same; Fig. 4 is a side elevation of a hand lever for varying the speed of the engine; Fig. 5 is a cross sectional view of a carbureter of the preferred form embodying the principles of my invention; Fig. 6 is a sectional view of the carbureter as taken on a line 6—6 of Fig. 5; Fig. 7 is a detail sectional view taken on a line 7—7 of Fig. 6; Fig. 8 is a sectional view taken on a line 8—8 of Fig. 7; Fig. 9 is a sectional view on

the line 9—9 of Fig. 5; Fig. 10 is a plan view of the operating lever for the butterfly valves.

It is desired to produce an engine of the combustion type which may be operated economically and efficiently at different speeds, thereby adapting it to be used for different purposes, without a greater loss of power or efficiency due to the use of a greater quantity of fuel than is absolutely necessary to perform the work desired. It is obvious that by varying the speed of an engine of this class the power can be correspondingly increased, provided, of course, that the engine will maintain the speed with a proper load. It is also manifest that the quantity of fuel required for the engine running under a heavy load is much more than that required for the same engine running under a light load. With the ordinary type of carbureter the fuel discharge opening for the engine is varied entirely by manual means, and the present invention is designed to overcome this difficulty by providing an automatic governing means to regulate the opening from the carbureter to the combustion chamber of the engine in accordance with the speed desired. It is also desirable that for any desired speed the variation of speed from the predetermined value should be as small as possible, and this necessitates that some means be provided for compensating for this variation for all different predetermined speeds.

The present invention provides means for varying the speed of the motor in a number of distinct steps with additional automatic means for preventing the variation of the speed of the engine from any one of these distinct steps under load. By varying the fuel inlet opening to the engine an economical use of the fuel is insured for the reason that only the approximate amount of fuel needed for this particular speed will be admitted to the engine. With this improved construction the speed of the engine can be kept substantially constant for any desired speed by simply varying the lever which is provided for that purpose.

Referring now more particularly to the drawings, and in the present exemplification of my invention, the numeral 11 designates the fly wheel of an engine having cylinders 12 and arranged on opposite sides of a shaft 13 to constitute an engine of the double opposed cylinder type. Meshing with a suit-

able gear on the shaft 13 is a gear 14 (see Figs. 2 and 3) which is secured to the shaft 15. This shaft 15 is effective to operate the valve rods 16 which control the supply and exhaust of gases to and from the cylinder in the well known manner. In the present exemplification of the invention as shown by Fig. 1, valve housings 17 are positioned above the cylinders 12, which are commonly provided with water jackets 18, and spark plugs 19 may be disposed therein at any desired or suitable place. The parts already described may be of any desired or suitable construction which is well known in the art, the arrangement being such as to form a mechanically and explosively balanced engine which does not require counter weights and with which a fly wheel, as 11, of the least weight may be employed in order to secure good regulation.

Pivotedly connected to some member which is fixed to the shaft 15, as for example to the gear 14, are the flyball members 20, which are provided with arms 21 which extend adjacent the shaft 15, and which are adapted to engage a collar 22 freely mounted thereon; as the shaft 15 is rotated the flyballs 20 will be thrown outwardly in accordance with the speed of rotation, and will cause the movement of the collar 22 along the shaft. A second collar 23 is also loosely mounted on the shaft, and connected to the collar 22 by means of a coil spring 24. At the outer end of the shaft and secured to the engine frame is a cap 25, which is preferably adapted to form a bearing for the outer end of the shaft 15 and is adapted to cover the gear 14 and the flyballs pivotally mounted thereon. Projecting inwardly from the cap 25 is a perforated ear or ears 26, which provide a bearing for a bar 27 extending substantially at right angles or transverse to the shaft 15. The outer end of the bar 27 protrudes at one side of the cap 25. At the inner end of the bar 27 secured thereto or formed integral therewith, is an arm 28 which is adapted to extend in proximity to the shaft 15, and is preferably bifurcated in form, as shown by Fig. 2, so that it will press equally against both sides of the collar. At the outer end of the bar 27, and secured thereto in any suitable manner, is a lever 29. This lever is disposed between the bifurcations 30 of a hand or adjusting lever 31, which are freely mounted upon the bar 27 and are adapted to provide a bearing support for the outer end of the bar. This lever 31 is movable about the bar 27 as an axis, and is moved in the perforated segment 32, which is secured by an extension 33 to any suitable portion of the frame or casting of the motor. The perforations in the segment 32 are for the purpose of constituting guides for the hand lever 31 in its various or different positions, and the hand

lever is adapted to be securely held in any adjusted position in the segment, but to be freely movable from any position into any other position. Extending downwardly from the bifurcations 30, and preferably formed integral with at least one of them, is an arm 34 (see Fig. 4), substantially the length of the downward extending portion of the lever 29, which is secured to the bar 27 between the bifurcated extremities 30 of the hand lever. Connecting the lower extremities of the levers 29 and 31 is a spring 35 which tends to oppose the separation of the downward extensions. It is evident, therefore, that if the hand lever 31 is turned in the segment 32, the lever 29 which is secured to the bar 27 will also be moved and the bar rotated in accordance therewith, since the tendency of the spring 35 is to keep the said levers in a certain spaced relation with respect to each other. Pivotedly connected to the downwardly extending portion of the lever 29 at a point intermediate of the lower end and the bar 27 is a connecting member 36 by means of which the fuel inlet passages of the carburetor to the engine are controlled. It is evident that the control is entirely automatic after being set for any desired speed, for the reason that the outward movement of the centrifugal device causes the bar 27 to be rotated in one direction while the spring 35 opposes this movement and causes the bar to be returned to its central position, so that the fluctuations of the speed of the engine will be entirely controlled by this device.

In combustion engines of this type, it has heretofore been customary to employ a carburetor or mixing device which is provided with only one discharge opening from the carburetor to the engine. The present invention embodies a carburetor which is provided with a plurality of fuel openings from the carburetor equal in number to the cylinders of the engine. In the preferred construction of this carburetor as shown by Figs. 1 and 5 to 10, inclusive, it will be seen that separate fuel inlet pipes 37 are provided for each of the cylinders of the engine. In the present exemplification of the invention two openings are shown in the carburetor.

The carburetor, in its preferred form, and as shown by the drawings, comprises a mixing chamber 39 and a float chamber 46, the mixing chamber being provided with inlet openings 40 and with a partition extending from the top of the chamber to a point below the lower edge of the said openings 40. An air inlet opening 42 is provided at the bottom of the chamber to admit air, and the top of the chamber is closed by a plate 43 which provides a bearing 44 for the opening lever 45. The mixing chamber has communication with the float chamber 46 by

means of the separate tubes 47, which extend upwardly from the lower portion of the float chamber across the mixing chamber 39, with an opening on the opposite side of the 5 mixing chamber through a boss 48. These tubes 47 are preferably spaced apart and located on opposite sides of the partition 41. Each tube 47 is provided with an opening 49 (see Fig. 7), which extends from the float 10 chamber, is enlarged at 50, and is provided at the outer end with internal threads to receive an adjusting screw 51 having a needle point 52, which is adapted to be moved into and out of the reduced portion 49 of the 15 tube by the adjustment of the screw 51. Locking screws 53 are preferably provided which may be moved in suitable threaded openings substantially at right angles to the openings for the adjusting screws 51 in the 20 boss 48 to engage the adjusting screws and to hold them in proper position. The tubes 47 are also provided with discharge nozzles 54 which communicate with the enlarged 25 portion 50 of the said tubes, and being connected to the tube in any suitable manner, such, for example, as through a projection 55 formed integral with each tube. These 30 discharge nozzles or projections 54 extend adjacent the openings 40 at one side thereof, so that the discharge of the fluid therefrom will be through the opening at all times, even though the opening is very slight.

To regulate and adjust the size of the 35 opening from the mixing chamber 39 into the tubes 37 which conduct the explosive mixture to the engine cylinders, pivotally mounted valves 56 are provided which are preferably rotated about a vertical axis in the openings 40 of the mixing chamber. 40 These pivoted valves 56 constitute what is commonly known as a butterfly valve, and the discharge nozzle is disposed so that the extremity thereof will be located at the edge of the valve when the valve 56 is in closed 45 position, so that even when the valve is nearly closed the fluid from the nozzle 54 will be projected through the opening and an explosive mixture will be supplied to the engine cylinders. This construction is adopted so that there will be no loss of the fuel, and so that there will be a proper and intimate mixture of the fuel and the air as it passes through the tubes 37 to the engine 50 cylinders. In order to operate the valves 55 bearing pins 57 are provided at one end, which are rigidly connected to the valves and which extend preferably through the top of the mixing chamber casing and through the top plate 43, and are formed 60 with crank ends 58. The operating lever 45, which is pivotally mounted on the cap plate 43 is provided with projections 59, which are adapted to receive the ends of the cranks 58, between them so that by rotating 65 the operating lever 45 about its point of piv-

otal support valves 56 will be opened and closed. These cranks 58 are so arranged that the valves 56 will be opened and closed in unison. One end of the operating lever 45 is provided with means for pivotal connection with the bar 36, which is also pivotally secured to the lever 29. It will therefore be evident that the operating lever 45 and the valve 56 will be operated in accordance with the movement of this lever 29. 70 The operation of the valves 56 is in a way in opposition to the operation of the engine, for the reason that the valves 56 are so connected that they tend to oppose the change in speed of the engine. That is to say, if 75 there is a deviation of the speed of the engine from the desired speed, the valves will be opened to oppose the deviation and to open or close the fuel supply openings from the carburetor to supply fuel in such a manner as to return the engine to the predetermined speed. If the engine has been set for a particular speed, and a lightening of the load causes the engine suddenly to speed up, the operating mechanism will cause the 80 valves 56 to be closed, whereupon a less supply of fuel will be admitted to the engine and the speed will be cut down. A similar operation occurs when the speed of the engine is suddenly reduced, whereupon the 85 valves will be opened much wider to admit more fuel to the engine. In this way the speed of the engine for any predetermined or desired speed is maintained practically constant. 90

To admit fuel to the float chamber 46 a gravity system and source of supply may be employed, comprising a suitable reservoir 60 and a tube 61 leading therefrom to the bottom of the float chamber. The float 105 chamber is preferably formed with a projection 62 at the bottom, which is formed with a recess 63 threaded at 64 from the interior of the float chamber (see Fig. 5). A screw plug 65 having a beveled valve 110 opening 66 is threaded into the recess at 64, and a valve 67 having a valve stem 68 is positioned therein, so that the valve 67 must be moved upwardly to close the valve opening. This valve stem extends upwardly 115 through the float chamber 46, and through a top plate 69, which covers the float chamber. The upper end of the valve stem may be depressed at any time to admit a greater quantity of fuel into the float chamber. In 120 order to maintain the fluid in the float chamber at a proper level, a float is provided, which is composed of any desired or suitable material. In the present exemplification of the invention a float 70 is provided 125 through which the valve stem 68 is inserted and along which the float may be moved. In order, however, to keep the float in any desired position and to adjust the position of the float along the valve stem without em- 130

ploying tools of any kind, a perforated strip of resilient material 71 is secured to the float 70. The ends of this flexible material are also perforated and are bent over until they overlap, and when pressed firmly against the float the perforations in the ends are adapted to register with each other and with an opening through the strip which is fixed to the float. In this position the valve stem 68 is freely inserted through the float and through the perforated strip. As soon, however, as pressure on the overlapping ends is relieved the resilience of the material presses them upwardly from the dotted position, as shown in Fig. 5, to the full line or normal position in the same figure, whereupon the valve stem will be gripped by the resilient material and the float will be held firmly in position without danger of slipping along the valve stem. To adjust the position of the float along the valve stem it is necessary only to press the folded over ends downwardly to their dotted position as shown in Fig. 5, whereupon the float may be moved 25 along the stem to any desired position.

The operation of the engine will be readily understood from the preceding description, and it is evident that it is necessary only to set the lever 31 for the desired speed of rotation of the engine, whereupon the automatic governing and fuel mixing device will maintain the speed of the engine practically constant for the desired speed. The speed of the engine may readily be changed 35 while the engine is in operation by simply varying the position of the lever 31, whereupon the governing and fuel mixing devices will automatically maintain the engine at the proper and desired speed. It is evident 40 that by this means the power of the engine may be varied through a wide range, and that the fuel consumption for any particular speed is adapted to that speed, so that at no time will a large amount of fuel and 45 power be expended in doing the useless work of moving a heavy and cumbersome machine. The applicant's engine is designed to be light in construction and the fly wheel is particularly light, for the reason that in 50 this type of motor the balance is so perfect, both mechanically and explosively, that a heavy fly wheel is not demanded. The term "explosively balanced" is applied to a machine in which there is an explosion for each 55 revolution of the fly wheel. As the four stroke cycle type of engine is referred to, this statement will be readily understood.

Although I have thus described the preferred embodiment of my invention, it is 60 evident that those skilled in the arts to which this relates may make various changes in the construction, combination and arrangement of the several parts without departing from the spirit and scope of the 65 invention.

What I claim is:—

1. The combination with a combustion engine having a plurality of cylinders, of an automatic carbureter having a mixing chamber provided with a separate outlet opening 70 for each engine cylinder, a partition extending from the top of the chamber below the lower edge of the said openings, valves for each outlet opening, and means controlled by the engine in connection with the valves 75 to operate them simultaneously in the same direction.

2. The combination with a gas engine having a plurality of cylinders, of a carbureter having a mixing chamber provided 80 with a separate outlet opening for each engine cylinder, valves for each outlet opening, a float chamber separate tubes connected to the mixing chamber and discharging adjacent each of the said outlet openings, 85 adjusting means for each of said tubes extending on the outside of the mixing chamber, and means in connection with the engine for operating the valves simultaneously.

3. The combination with a gas engine 90 having a plurality of cylinders, of a carbureter having a mixing chamber provided with a separate outlet opening for each engine cylinder, valves for each outlet opening, a float chamber connected to the mixing 95 chamber by separate tubes and discharging adjacent each of the said outlet openings, adjusting means for each of said tubes extending on the outside of the mixing chamber, set screws for said adjusting means, 100 and means in connection with and depending upon the speed of the engine for operating the valves simultaneously.

4. The combination with an engine of the class described and comprising a rotatable shaft, collars freely mounted on said shaft, a coil spring flexibly connecting said collars, pivotally mounted members actuated by centrifugal force and operative to engage one of said collars by their movement to effect a 105 movement of the other collar along the shaft, a bar transverse to the shaft having an arm engaged by the last named collar and an arm on the other end, a fuel mixing device for the engine having valves to control 110 fuel supply to the engine, a lever connected to the said valves, a member connected to one end of said last named lever and to the last mentioned arm to actuate the said valves in accordance with the movement of the 115 said centrifugal members, a hand lever pivotally mounted on said transverse bar at the outer end having a downward extension substantially as long as the downwardly extending arm at this end, and a spring connecting the extension and the said arm tending normally to oppose their separation, the said hand lever being adjustable into different fixed positions and operative in conjunction with said centrifugal members to allow 120 125 130

a variation of and to maintain the valves of the fuel supply device substantially in a position corresponding to any fixed position of the said hand lever whereby the speed of the engine will be maintained practically constant for this position.

In testimony whereof I have signed my

name to this specification, in the presence of two subscribing witnesses, on this 23rd day of April, A. D. 1912.

WILLIAM L. PHILLIPS.
